CHILD'S MUFF

Sarah Klein, Brooklyn, N. Y., assignor to Merry Products,
Inc., Brooklyn, N. Y., a corporation of New York

Application February 21, 1955, Serial No. 34,588

Term of patent 7 years

(Cl. D3—2)

FIG. 1.

FIG. 2.

Fig. 1 is a front elevational view of a child's muff, showing my new design.

Fig. 2 is a side elevational view thereof.

Fig. 3 is a rear elevational view thereof.

I claim:

The ornamental design for a child's muff, substantially as shown.
